MACHINE FOR EXTRUDING HOLLOW CORED CONCRETE SECTIONS

Fredrick G. Ellis, 248 Egerton Road, and Marvin A. Thorsteinson, 67 Kingston Row, both of Winnipeg, Manitoba, Canada

Filed July 10, 1961, Ser. No. 122,698
11 Claims. (Cl. 25—41)

Our invention relates to new and useful improvements in machines for extruding hollow cored concrete sections.

Precast concrete floor and roof sections are normally cast in lengths and then fitted together at the site. The conventional and present day precast concrete floor and roof sections are made normally from reinforced concrete and apertured longitudinally.

It is conventional to pour these sections in a mould containing longitudinally extending flexible cores which are then inflated whereupon the concrete is allowed to cure, the cores are deflated and then withdrawn therefrom.

Not only is it difficult to manufacture panels of considerable length but it will be appreciated that the cores and the moulds cannot be reused until sufficient curing takes place.

This makes the manufacture of such panels relatively expensive and time consuming and this, together with the limitations of the mould, insofar as length is concerned, makes manufacturing relatively difficult.

Furthermore the equipment required for the manufacture of such slabs is relatively expensive and necessitates considerable capital investment.

We have overcome all of these disadvantages by providing a longitudinally extending pallet or supporting surface of any desired length, a supporting framework adapted to be self propelled along the supporting surface or pallet, a product forming assembly including a feeding section, a moulding section and a trowelling section, together with an auger extending through these sections adapted to force the material from the hopper, to the moulding section and out past the trowelling section thus not only forming the exterior surfaces of the slab but also forming the longitudinally extending apertures. Furthermore the auger compresses the concrete to the desired density and the reaction of the compressed concrete with the inertia of the finished slab on the supporting surface or pallet self propels or retrudges the machine continuously along said supporting surface or pallet.

Inasmuch as the machine is relatively simple in construction, we have found that we can manufacture slabs on a continuous basis up to any desired length either reinforced or not reinforced, simply and economically.

The principal object and essence of our invention is therefore to provide a device of the character herewithin described which is adapted to produce a longitudinally extending cored concrete product which, due to the viscosity of the mix used, is self supporting once it has been vibrated and compressed by the forming action of the machine.

Another object of our invention is to provide a device of the character herewithin described which permits slabs to be formed in any desired length inasmuch as the finished product can be sawn in situ as soon as it has begun to cure.

Another object of our invention is to provide a device of the character herewithin described in which the panels can be made with parallel sides or sloping sides, the latter being particularly useful for use in the manufacture of silos or grain bins.

Yet another object of our invention is to provide a device of the character herewithin described which can be manufactured with one or more longitudinal apertures

2

extending therethrough depending upon the number of augers utilized.

Still another object of our invention is to provide a device of the character herewithin described which is particularly suited for the construction of slabs in which the aperture formed therein is of a vertical oval configuration thus giving additional strength to the finished structure.

Still another object of our invention is to provide a device of the character herewithin described in which the density of the finished product can be controlled within limits by increasing or decreasing the frictional resistance of the machine upon the pallet or supporting surface.

A still further object of our invention is to provide a device of the character herewithin described which is relatively simple in construction, economical in manufacture and otherwise particularly well suited to the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

FIGURE 1 is an isometric view of our device with the hopper and product forming assembly removed for clarity.

FIGURE 2 is an isometric view of our device showing the hopper, the moulding section, and the trowelling section, in a separated condition for clarity.

FIGURE 3 is an end view, reduced in scale from FIGURES 1 and 2 and showing the drive connection to the three augers.

FIGURE 4 is a fragmentary isometric view of one end 35 of a modified pallet showing the starting bulkhead and also, in phantom, a portion of the finished product.

FIGURE 5 shows a side elevation of one embodiment of the augers.

FIGURE 6 shows a side elevation of an alternative embodiment of the augers.

FIGURE 7 is a fragmentary end view of the auger supporting blocks, showing its relation to the supporting pallet.

FIGURE 8 is an isometric view of one type of product which can be manufactured by the device.

FIGURE 9 is an isometric view of an alternative type of product which can be manufactured by the device.

FIGURE 10 is an isometric fragmentary view showing a reinforcing cage in situ upon the pallet.

FIGURE 11 is a top plan view of the pallet side straightening rollers.

FIGURE 12 is an end view of FIGURE 11.

FIGURE 13 is an isometric view of the core used between two augers to give an oval aperture within the product.

FIGURE 14 is an end view of the trowelling mandrels one above the other with the core of FIGURE 13 in situ.

FIGURE 15 is a side elevation of the machine.

In the drawings like characters of reference indicate corresponding parts in the different figures.

Proceeding therefore to describe our invention in detail, reference should be made to the accompanying drawings in which we have illustrated our device. It is designed primarily to be used upon a pallet 10 consisting of a planar base 11 and upstanding edge flanges 12. However, it will be appreciated that, if desired, the device could be used upon any supporting surface provided means are present to guide the device along the desired path.

The machine collectively designated 13 consists of a main frame collectively designated 14 which includes longitudinally extending side members 15 in the form of

outwardly facing channels. These channels are maintained in spaced apart parallel relationship by means of cross members 17 secured thereto. These cross members 17 in turn support a source of power in the form of an electric motor 18 mounted upon a heavy duty reduction gear box 19. A belt 20 extends between the electric motor and gear box and the drive from the reduction gear box is carried by the drive shaft 21 extending rearwardly therefrom.

Rearwardly of the gear box and source of power is a product forming assembly shown in the expanded view of FIGURE 2. This product forming assembly, which is mounted on the aforementioned longitudinal channels 15, consists of a feeding section 22, a moulding section 23, and a trowelling section 24, it being understood that when the machine is assembled, all three sections are adjacently connected to one another between the channels 15.

The feeding section 22 includes a feed hopper 25 mounted between channels 15 and including downwardly extending sides 23 adapted to funnel the product forming material from the hopper downwardly between the plates 26.

The moulding section 23 consists of an upper plate 27 and two downwardly depending side plates 28, the lower edges 29 of which are adapted to register just above the upper surfaces 30 of the pallet side flanges 12. The clearances between the edges 29 and the surfaces 30 are maintained by a transverse support plate 31 secured to the upper surface of the plate 27 by means of the vertical struts 32.

Upon the underside of the plate 31 we provide resilient spacers 33 which are secured to the plate 31 and to the top flanges 34 of the channel members thus suspending the moulding section 23 in the desired position.

We also provide a vibrating unit 34' mounted upon the plate 31 and this vibrating unit is operated from a source of power (not illustrated) so that vibration is given to the moulding section during operation thus assisting in the flowing of the product forming material passing thereby.

The trowelling section consists of an upper transverse plate 35 and two downwardly depending side plates 36. A boxing 37 is secured to the plate 35 and may be utilized to load the trowelling section if desired.

This trowelling plate is secured to the moulding section 23 by means of loose bolts 32' attaching to struts 32 so that it will be maintained in close contact to the moulding section but will not transmit the vibration therefrom.

I have found it desirable that the side plates 36 of the moulding section extend rearwardly of the plate 35 in order to maintain the formed product in the desired configuration remotely from the source 34' of the packing vibration.

It will be appreciated that the feeding, moulding and trowelling sections hereinbefore described cooperate with the planar base 11 of the pallet to form the product as will hereinafter be described.

Referring back to FIGURE 1, the drive 21 extending from the reduction gear box 19 is supported within a bearing 38 in turn supported upon a bearing box 39 secured to the aforementioned longitudinal frame members 15.

Journalled for rotation within the box 39 and a rear bearing plate 40 is a plurality of augers 41. In this particular embodiment three such augers have been provided but it will be appreciated that this number can be varied as desired.

The portion of the auger shaft between the bearing box 39 and the rear bearing plate 40 carries chain sprockets 42 and a pair of idler sprockets 43 are journalled for rotation upon a transverse bracket 44 above the level of the aforementioned sprockets 42.

The shaft 21 is provided with a drive sprocket 45 and an endless chain 46 extends around this drive

sprocket, and around the sprockets 42 and 43 alternatively as clearly shown in FIGURE 3, thus ensuring that all of the augers rotate in the same direction.

Reference to FIGURE 5 will show the preferred construction of our augers which consist of an auger shaft 47 having an auger flight 48 formed thereon.

The portion 49 of the shaft within the feeding section is parallel whereas the portion 50 within the moulding section gradually increases in diameter to the maximum diameter as indicated by the reference character 51 and provides means in association with the surrounding moulding section, to radially compress the product forming material as it passes therethrough.

It will also be observed that the diameter of the auger flight is constant but, due to the enlarging of the auger shaft 50, the depth of the auger flight decreases to zero.

Extending beyond the point 51 of the auger shaft, we have provided parallel, cylindrical trowelling mandrels 52 and these trowelling mandrels are adapted to rotate within the trowelling section 24 of the assembly. The diameter of the trowelling mandrel is the same as the diameter of the auger flight and the depth of the flight therefore decreases to zero, as aforesaid, at the beginning of the trowelling mandrel.

Therefore, when installed, the portion 47 of the auger is within the feeding section of the product forming assembly, the tapered portions 49 is within the moulding section, and the cylindrical mandrels 52 are within the trowelling section.

The entire machine, if designed to operate with the aforementioned pallet 10, is mounted for longitudinal movement upon the pallet by the provision of rollers or wheels 53 journalled for rotation adjacent the lower sides 54 of the aforementioned channels 15 and these wheels or rollers are adapted to engage the upper edges 30 of the side flanges 12 of the pallet.

In order to maintain the device upon the edges of the pallet, further rollers or wheels 55 are journalled for rotation upon the underside of the channels 15, said wheels 40 lying at right angles to the aforementioned wheels 53 and engaging the side faces 56 of the flanges 12 all of which is clearly shown in FIGURE 7.

In operation to this point, reference should first be made to FIGURE 4 in which we have shown a starting bulkhead 57 consisting of a vertically situated plate 58 and two extending side plates 59. This device is clamped within the end of the pallet 10 and is provided with three apertures 60 within the plate 58 adapted to be engaged by the ends 61 of the mandrels 52.

The desired mix of the right consistency and fluidity is fed into the hopper 25 and flows by gravity to between the side plates 26 and into the feeding section of the assembly.

The source of power is activated thus causing the augers to rotate which feeds the product forwardly towards the moulding section 27 which is being vibrated by the vibrator 34.

Due to the tapering of the auger shaft 50 at this point, the product is compressed and fluidity is maintained due to the vibrator thus causing same to be packed tightly around the augers and between the side plates 28, the upper plates 27 and the floor of the pallet.

The compressed product is then forced through the trowelling section which smooths the side and top of the product and sizes same accurately. It then engages the bulkhead 58 hereinbefore described and due to the fact that the augers are continuously forcing material from the hopper rearwardly through the moulding section and through the trowelling section, the machine is thus urged away or retruded from the bulkhead thus leaving the product therebehind. The mandrels 52 trowel the inner bores 62 of the product 63 shown in FIGURE 8 thus resulting in an accurate smooth continuously produced hollow cored section. As long as material is fed into the hopper 25, it will be appreciated that the product will

continue to be produced to the limit of the length of the pallet 10.

Due to the relative dryness of the mix used and due to the compressibility induced by the auger and the vibrator, the product is self supporting just as soon as the machine passes thereover and is produced without any voids or weak areas occurring.

If it is desired to form keyways 64, within the sides of the product the necessary beads or dowels 66 can be secured to the inner faces of the side plates 36 of the trowelling section.

The relationship of the side plates 36 of the trowelling section and the side plates 28 of the moulding section decide the relationship of the sides 67 of the product. If these plates are parallel, then a product will be formed having sides similar to that shown in FIGURE 8.

If, however, it is desired to form a product as shown in FIGURE 9 with sloping sides 68, then all that is necessary is to slope the plates 26 and 28 so that the sides of the product will be formed in a similar manner. This particular construction is suitable for vertical erection in ring formation for the manufacture of silos, grain storage bins or other cylindrical structures.

It is often desirable that products of this nature be reinforced and our device is particularly suited for use with conventional reinforcing which is shown in FIGURE 10.

A reinforcing cage 69 is manufactured by the provision of a plurality of steel rods 70 held together by means of stirrups 71 at spaced intervals therealong and secured by welding or the like.

This reinforcing cage is laid first upon the pallet and positioned above the base by the provision of stirrups 72 at convenient positions along the length thereof.

The bearing box 39 is apertured as at 73 on the lower edge thereof to allow the machine to pass over the rods 70 as it moves forwardly.

There is sufficient clearance around the bearing box and other portions of the machine to allow free passage of the machine over the cage 69 so that the material is compacted and formed around the reinforcing cage in position upon the pallet.

FIGURE 6 shows an alternative form of auger construction in which the shaft 47 is parallel throughout its length and the auger flight 48 is of the same depth. In this instance, of course, the trowelling mandrel 52 is secured to the end of the shaft 47 and the vertical shoulder 74 formed between the shaft and the mandrel 52 permits the auger to generate sufficient compression in order to accomplish the necessary pressure to pack the material and to self propel the machine along the pallet.

In both instances, of course, it will be realized that the diameter of the auger flight 48 is constant and that in the embodiment shown in FIGURE 5, although the auger flight disappears at the point 51, this is due to the increase in diameter of the shaft up to the diameter of the trowelling mandrel 52.

It is necessary to control, within limits, the resistance offered by the machine to movement along the pallet as this of course will control the compressive density of the finished product.

By providing spring loaded adjustable side flange engaging clamps 74 secured to the members 15 forwardly of the machine, we can control the frictional resistance of the machine along the pallet. These spring loaded clamps can be adjusted to give a greater or lesser frictional engagement with side flanges. They also act to clean the flanges prior to the machine passing thereover, a point that is essential to the production of a consistent product.

Also, it is desirable that the side flanges be maintained in a true, parallel position one with the other and in this connection reference should be made to FIGURES 11 and 12.

An extension plate 76 to the side members 15 carries a plurality of rollers 77 journalled upon pins 78 and situated alternately upon each side of the side flanges. These

of course, are engaged upon each side of the side flanges 10 of the pallet and as the machine moves along the pallet, these rollers true the verticality of the side flanges prior to the machine passing thereover.

Reference should next be made to FIGURES 13 and 14 in which we have shown a modification of our device, thus permitting us to provide a product having a vertically situated substantially oval core or aperture therethrough, a design often needed for additional strength.

In this instance we provide pairs of augers one upon the other designated 79 in these drawings.

A stationary spindle 80 is adapted to be secured to the bearing box 39 and extend parallel with the pair of augers, said spindle carrying a stationary transversely situated core block 81 upon the end thereof and between the trowelling mandrels 82 of the two vertically situated augers. The upper and lower surfaces 83 of this core block are concaved as shown in FIGURE 13 so that the mandrels nest therewithin and the width of the core block is substantially similar to the diameter of the mandrels.

From the foregoing it will be appreciated that the augers will force the material through the machine as hereinbefore described in previous embodiments but that the core or apertures formed will be vertically oval due to the provision of the two augers and mandrels with the stationary core block therebetween.

By tilting this core block slightly, the corners 84 thereof engage the leading surfaces of the mandrels thus maintaining same in a clean condition.

FIGURE 5 also shows an alternative addition to the auger in order to facilitate the trowelling action and to ensure the smooth finish is supplied to the bores. We mount a trowelling mandrel extension 85 having a cylindrical configuration similar to the mandrel 52.

This mandrel is shouldered as the inner end thereof as at 86 and is adapted to be journalled within a bearing 87 secured within the end of the mandrel 52.

It will therefore be appreciated that as the mandrel is rotated and withdrawn from the bore of the product, the section 85 may remain stationary due to the bearing 87 thus acting as a smoothing portion and at the same time the bearing 87 isolates the portion 85 from any residual vibration from the vibrator 34' which may be present in the augers.

A further improvement is shown in FIGURE 6 in which the trowelling mandrel 52 is provided with a shaft 88 extending axially therefrom and offset slightly from the center line. A rolling mandrel 89 is journalled to this shaft by bearings 90 and therefore rolls in the formed bore 62 of a circumference slightly greater than the circumference of the mandrel 52 thus adding extra compression to the material surrounding the bore. Although this is shown in conjunction with the auger in FIGURE 6 it can, of course, be used with the type of auger shown in FIGURE 5.

Furthermore, the mandrel 85 shown in FIGURE 5 can be added on to the rolling mandrel 89 providing the shaft 88 is recentered at this point so that the mandrel 85 follows the formed bore.

In FIGURE 1, the preferred modification to the mandrel 52 is shown, also to reduce vibration effects from the vibrator to the finished bore 62 of the product.

A spindle 90 is formed on the end of the mandrel 52 and a rubber block 91 surrounds this spindle and registers against the shoulder 92.

A hollow mandrel 93, shouldered internally at 95, registers against the block 91 and a rubber washer 95 engages over the spindle 90 and against the shoulder 94. A washer and nut 96 engages the screw-threaded end of the spindle 90 and secures the assembly in place.

The mandrel 93 trowels the finish of the bores 62, but does not transmit vibration thereto.

Reference should next be made to FIGURE 7, in which we have shown an arcuate or convexedly curved packing

plate 97 secured to the underside of the plate 27 beneath the vibrator. This plate 97 extends rearwardly part way along the length of the plate 27 and converges to a point so that it is triangular when viewed in plan. The edges 98 merge into the planer undersurface of the plate 27. The vibration of this plate, due to the vibrator, urges the material outwardly and ensures that the upper corners of the product are square. It also prevents cavitation occurring of the upper surface of the product, a situation which tends to occur under certain mixture density conditions, if the plate 27 is completely planar.

Finally reference to FIGURES 5 and 7 show the incorporation of semi cylindrical shields 99 secured by one end 100 thereof to the wall 101 of the box 39 and extend alongside one or more of the augers 41 in spaced and parallel relationship thereto.

The upper edges 102 (see FIGURE 5) of these shields, are substantially parallel to the longitudinal axis of the auger for the first part of its length and then this upper edge tapers downwardly to meet the lower edge 103 as shown at 104.

These shields eliminate some of the side thrust developed by the augers thereby eliminating turbulence around the reinforcing wires 70 of the product forming material. This turbulence has the effect, under certain operating conditions, of forming voids around the wires and the elimination of these voids is desirable.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What we claim as our invention is:

1. A machine for forming hollow cored concrete sections on a longitudinally extending supporting surface, comprising in combination a main frame, said main frame including a pair of spaced and parallel longitudinal members, means to support and guide said main frame along said supporting surface, a source of power mounted on said main frame, a product forming assembly mounted between said longitudinal members, said product forming assembly including a feeding section, a moulding section, and a trowelling section in line with one another, a feed hopper mounted on said main frame and leading into said feeding section, at least one auger supported for rotation at one end thereof adjacent said feeding section and extending through said feeding section and said moulding section substantially parallel to said supporting surface and spaced therefrom and lying substantially parallel with the longitudinal axis of said machine, said auger being connected for rotation to said source of power, and a trowelling mandrel on the other end of said auger within said trowelling section, said auger adapted to convey product forming material from the base of said hopper, through said moulding section and into said trowelling section, and means on said auger, which in conjunction with said moulding section, are adapted to compress said material radially whereby the reaction of said compression with the inertia of the finished product therebehind, self propels said machine along said supporting surface and away from the product formed by said moulding section thereby drawing said trowelling section over said formed product, said auger including an auger shaft and an auger flight formed thereon, the outer diameter of said auger flight being substantially constant, the portion of said shaft in said feeding section having a substantially constant diameter, said last mentioned means on said shaft including the portion of said shaft in said moulding section, said last mentioned portion gradually increasing in diameter to the diameter of said trowelling mandrel whereby the depth of said auger flight decreases to zero adjacent the area joining said trowelling mandrel and the end of said auger shaft,

and a vibrator above said moulding section, a source of power for said vibrator, said vibrator adapted to vibrate said moulding section.

2. The device according to claim 1 in which said moulding section includes a pair of side plates and a top plate spanning said side plate thereby forming, in conjunction with said supporting surface, a mould box adapted to size the resultant product as it is formed thereby.

3. The device according to claim 1 in which said trowelling section includes a pair of side plates situated between said longitudinal members one adjacent each of said longitudinal members, the position of said side plates determining the relation of the sides of the finished product to one another.

4. The device according to claim 1 which includes two augers one above the other and a stationary core portion mounted on said main frame and extending between said two augers, said core portion including a spindle extending through said feeding section and said moulding section, and a core mounted on the end of said spindle and lying transversely between said trowelling mandrels, the upper and lower faces of said core being concave whereby said trowelling mandrels nest therein, the transverse width of said core being substantially the same as the diameter of said mandrels thereby forming a vertically situated substantially oval, hollow core in said product.

5. The device according to claim 1 which includes a trowelling mandrel extension journaled upon the end of said trowelling mandrel and having a diameter similar thereto.

6. A machine for extruding hollow cored concrete sections on a longitudinally extending supporting surface, comprising in combination a main frame, said main frame including a pair of spaced and parallel longitudinal members, said supporting surface taking the form of a longitudinally extending pallet including a planar base and upstanding side flange edges upon each side edge of said base substantially at right angles thereto, means to support and guide said main frame along said pallet, said means including a plurality of rollers journaled for rotation on said main frame on the underside thereof and engaging the upper edges of said side flanges, and further rollers also journaled for rotation on the underside of said main frame at right angles to said first mentioned rollers and adapted to engage the vertical sides of said side flanges, a source of power mounted on said main frame, said main frame including a pair of spaced and parallel longitudinal members, a product forming assembly mounted between said longitudinal members,

40 said product forming assembly including a feeding section, a moulding section and a trowelling section in line with one another, a feed hopper mounted on said main frame and leading into said feeding section, at least one auger supported for rotation at one end thereof adjacent said feeding section and extending through said feeding section and said moulding section substantially parallel to said supporting surface and spaced therefrom and lying substantially parallel with the longitudinal axis of said machine, said auger being connected for rotation to said source of power, and a trowelling section, said auger adapted to convey product forming material from the base of said hopper, through said moulding section and into said trowelling section, and means on said auger, which in conjunction with said moulding section, are adapted to compress said material radially whereby the reaction of said compression with the inertia of the finished product therebehind, self propels said machine along said supporting surface and away from the product formed by said moulding section thereby drawing said trowelling section over said formed product, said auger including an auger shaft and an auger flight formed thereon, the outer diameter of said auger flight being substantially constant, the portion of said shaft in said feeding section having a substantially constant diameter, said last mentioned means on said shaft including the portion of said shaft in said moulding section, said last mentioned portion gradually increasing in diameter to the diameter of said trowelling mandrel whereby the depth of said auger flight decreases to zero adjacent the area joining said trowelling mandrel and the end of said auger shaft,

45 said trowelling mandrel extension journaled upon the end of said trowelling mandrel and having a diameter similar thereto.

5. The device according to claim 1 which includes a trowelling mandrel extension journaled upon the end of said trowelling mandrel and having a diameter similar thereto.

6. A machine for extruding hollow cored concrete sections on a longitudinally extending supporting surface, comprising in combination a main frame, said main frame including a pair of spaced and parallel longitudinal members, said supporting surface taking the form of a longitudinally extending pallet including a planar base and upstanding side flange edges upon each side edge of said base substantially at right angles thereto, means to support and guide said main frame along said pallet, said means including a plurality of rollers journaled for rotation on said main frame on the underside thereof and engaging the upper edges of said side flanges, and further rollers also journaled for rotation on the underside of said main frame at right angles to said first mentioned rollers and adapted to engage the vertical sides of said side flanges, a source of power mounted on said main frame, said main frame including a pair of spaced and parallel longitudinal members, a product forming assembly mounted between said longitudinal members,

50 said product forming assembly including a feeding section, a moulding section and a trowelling section in line with one another, a feed hopper mounted on said main frame and leading into said feeding section, at least one auger supported for rotation at one end thereof adjacent said feeding section and extending through said feeding section and said moulding section substantially parallel to said supporting surface and spaced therefrom and lying substantially parallel with the longitudinal axis of said machine, said auger being connected for rotation to said source of power, and a trowelling section, said auger adapted to convey product forming material from the base of said hopper, through said moulding section and into said trowelling section, and means on said auger, which in conjunction with said moulding section, are adapted to compress said material radially whereby the reaction of said compression with the inertia of the finished product therebehind, self propels said machine along said supporting surface and away from the product formed by said moulding section thereby drawing said trowelling section over said formed product, said auger including an auger shaft and an auger flight formed thereon, the outer diameter of said auger flight being substantially constant, the portion of said shaft in said feeding section having a substantially constant diameter, said last mentioned means on said shaft including the portion of said shaft in said moulding section, said last mentioned portion gradually increasing in diameter to the diameter of said trowelling mandrel whereby the depth of said auger flight decreases to zero adjacent the area joining said trowelling mandrel and the end of said auger shaft,

55 said trowelling mandrel extension journaled upon the end of said trowelling mandrel and having a diameter similar thereto.

6. A machine for extruding hollow cored concrete sections on a longitudinally extending supporting surface, comprising in combination a main frame, said main frame including a pair of spaced and parallel longitudinal members, said supporting surface taking the form of a longitudinally extending pallet including a planar base and upstanding side flange edges upon each side edge of said base substantially at right angles thereto, means to support and guide said main frame along said pallet, said means including a plurality of rollers journaled for rotation on said main frame on the underside thereof and engaging the upper edges of said side flanges, and further rollers also journaled for rotation on the underside of said main frame at right angles to said first mentioned rollers and adapted to engage the vertical sides of said side flanges, a source of power mounted on said main frame, said main frame including a pair of spaced and parallel longitudinal members, a product forming assembly mounted between said longitudinal members,

60 said product forming assembly including a feeding section, a moulding section and a trowelling section in line with one another, a feed hopper mounted on said main frame and leading into said feeding section, at least one auger supported for rotation at one end thereof adjacent said feeding section and extending through said feeding section and said moulding section substantially parallel to said supporting surface and spaced therefrom and lying substantially parallel with the longitudinal axis of said machine, said auger being connected for rotation to said source of power, and a trowelling section, said auger adapted to convey product forming material from the base of said hopper, through said moulding section and into said trowelling section, and means on said auger, which in conjunction with said moulding section, are adapted to compress said material radially whereby the reaction of said compression with the inertia of the finished product therebehind, self propels said machine along said supporting surface and away from the product formed by said moulding section thereby drawing said trowelling section over said formed product, said auger including an auger shaft and an auger flight formed thereon, the outer diameter of said auger flight being substantially constant, the portion of said shaft in said feeding section having a substantially constant diameter, said last mentioned means on said shaft including the portion of said shaft in said moulding section, said last mentioned portion gradually increasing in diameter to the diameter of said trowelling mandrel whereby the depth of said auger flight decreases to zero adjacent the area joining said trowelling mandrel and the end of said auger shaft,

65 said trowelling mandrel extension journaled upon the end of said trowelling mandrel and having a diameter similar thereto.

6. A machine for extruding hollow cored concrete sections on a longitudinally extending supporting surface, comprising in combination a main frame, said main frame including a pair of spaced and parallel longitudinal members, said supporting surface taking the form of a longitudinally extending pallet including a planar base and upstanding side flange edges upon each side edge of said base substantially at right angles thereto, means to support and guide said main frame along said pallet, said means including a plurality of rollers journaled for rotation on said main frame on the underside thereof and engaging the upper edges of said side flanges, and further rollers also journaled for rotation on the underside of said main frame at right angles to said first mentioned rollers and adapted to engage the vertical sides of said side flanges, a source of power mounted on said main frame, said main frame including a pair of spaced and parallel longitudinal members, a product forming assembly mounted between said longitudinal members,

70 said product forming assembly including a feeding section, a moulding section and a trowelling section in line with one another, a feed hopper mounted on said main frame and leading into said feeding section, at least one auger supported for rotation at one end thereof adjacent said feeding section and extending through said feeding section and said moulding section substantially parallel to said supporting surface and spaced therefrom and lying substantially parallel with the longitudinal axis of said machine, said auger being connected for rotation to said source of power, and a trowelling section, said auger adapted to convey product forming material from the base of said hopper, through said moulding section and into said trowelling section, and means on said auger, which in conjunction with said moulding section, are adapted to compress said material radially whereby the reaction of said compression with the inertia of the finished product therebehind, self propels said machine along said supporting surface and away from the product formed by said moulding section thereby drawing said trowelling section over said formed product, said auger including an auger shaft and an auger flight formed thereon, the outer diameter of said auger flight being substantially constant, the portion of said shaft in said feeding section having a substantially constant diameter, said last mentioned means on said shaft including the portion of said shaft in said moulding section, said last mentioned portion gradually increasing in diameter to the diameter of said trowelling mandrel whereby the depth of said auger flight decreases to zero adjacent the area joining said trowelling mandrel and the end of said auger shaft,

75 said trowelling mandrel extension journaled upon the end of said trowelling mandrel and having a diameter similar thereto.

said shaft in said moulding section, said last mentioned portion gradually increasing in diameter to the diameter of said trowelling mandrel whereby the depth of said auger flight decreases to zero at the area between said trowelling mandrel and the end of said auger shaft, a vibrator above said moulding section, and a source of power for said vibrator, said vibrator adapted to vibrate said moulding section.

7. The device according to claim 6 in which said moulding section includes a pair of side plates and a top plate spanning said side plate thereby forming, in conjunction with said supporting surface, a mould box adapted to size the resultant product as it is formed thereby.

8. The device according to claim 6 in which said trowelling section includes a pair of side plates situated between said longitudinal members one adjacent each of said longitudinal members, the position of said side plates determining the relation of the sides of the finished product to one another.

9. The device according to claim 6 which includes two augers one above the other and a stationary core portion mounted on said main frame and extending between said two augers, said core portion including a spindle extending through said feeding section and said moulding section, and a core mounted on the end of said spindle and lying transversely between said trowelling mandrels, the upper and lower faces of said core being concave whereby said trowelling mandrels nest therein, the transverse width of said core being substantially the same as the diameter of said mandrels thereby forming a vertically situated substantially oval, hollow core in said product.

10. The device according to claim 6 which includes a trowelling mandrel extension journaled upon the end of said trowelling mandrel and having a diameter similar thereto.

11. An auger for use in forming hollow cored concrete sections, said auger including a shaft supported for rotation by one end thereof, and an auger flight formed on said shaft, the diameter of said auger flight being constant, said shaft including a portion adjacent said one end having a constant diameter and an adjacent portion extending from said first mentioned portion in which the diameter increases uniformly to the diameter of said auger flight so that the depth of said auger flight decreases to zero, and a trowelling mandrel adjacently forms an extension of said second mentioned portion of said shaft, the diameter of said trowelling mandrel being similar to the diameter of said flight.
